(57) **CLAIM**

The ornamental design for a combined earphone and charger, as shown and described.

DESCRIPTION

FIG. 1 is a perspective view of a charger of a combined earphone and charger, shown separately to show aspects of the design that are not visible when combined, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the combined earphone and charger shown combined;

FIG. 9 is a perspective view of the combined earphone and charger shown in a closed position;

FIG. 10 is a front perspective view of an earphones of the combined earphone and charger shown separately to show aspects of the design that are not visible when combined;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof; and,

FIG. 17 is a rear perspective view thereof.

The broken lines in the drawings depict portions of the combined earphone and charger that form no part of the claimed design.
